UNITED STATES PATENT OFFICE.

IDA M. HEATH, OF SEATTLE, WASHINGTON.

CULINARY UTENSIL.

Application filed May 22, 1922. Serial No. 562,742.

To all whom it may concern:

Be it known that I, IDA M. HEATH, a citizen of the United States of America, residing at Seattle, in the county of King and State of Washington, have invented certain new and useful Improvements in Culinary Utensils, of which the following is a specification, reference being had therein to the accompanying drawings.

10 The invention relates to a culinary utensil which may be used as a flour sifter, a fruit colander and for other like purposes.

It is the object of the present invention to provide an inexpensive and simplified device of the character referred to, constructed in such manner that different screens or sieves of varying mesh may be used interchangeably in the same device. A further object of the invention is to so construct the 20 device that all of its parts may be completely and readily disassembled and reassembled, which feature facilitates cleaning of the parts as well as repair or substitution thereof. Structural features pertaining to assembly, 25 the particular type of agitator used and other combinations and arrangement of parts are hereinafter more fully described and illustrated in the accompanying drawings wherein:—

30 Figure 1 is a front elevation of the device;

Figure 2 is a cross section on the line 2—2 of Figure 1;

35 Figure 3 is a plan view of the agitator detached showing the twisted blades.

Describing in detail A represents a sifting device composed of upper and lower sections B and C respectively, detachably hinged to each other at D. The upper section B is provided with a handle B', the lower end of which is secured adjacent the lower edge of the section and provided with an upturned tongue B². The lower section has its upper edge bent about a wire C' except at one point where the wire is bent up to form a loop C² through which the tongue B² is inserted. This tongue engaging the loop forms said hinge D as shown in Figure 2. Diametrically opposite 45 from the hinge is a latch E for holding the two sections tightly together when the device is in use. This latch comprises a bracket F riveted, soldered or otherwise secured to the lower section C and near the upper 50 edge thereof. A small lever F', preferably formed of wire, is pivotally mounted on

said bracket at F² and carries a wire loop F³ also pivotally mounted at F⁴. Directly above the bracket the section B is provided with a tongue G over which the wire F³ is placed before the lever F' is pressed down to lock the sections together. This wire F³ is slightly bent near its pivot to prevent the latch from accidental release when the lever F' is pressed all the way down. 65

While it is proposed to put the present invention upon the market in the form of a set including the device itself with a sieve of medium mesh therein and two extra strainers or sieves of fine and heavy mesh respectively. The following illustration will suffice as to the construction of the sieves, as each are the same except as to the size of the mesh used. H represents a bowl shaped sieve having a slightly curved rim H' adapted to set snugly over the upper rolled rim of the lower section C. When the sections are locked together the lower edge of the section B which is also curved will fit tightly over the curved rim H' of 80 the sieve which in turn snugly fits the rolled upper rim of the lower section C thus forming a relatively tight joint between the parts and securely clamping the sieve in position. 75

The agitator I is so constructed as to press 85 the contents it engages against the mesh of the sieve and at the same time break up the mass and move it toward the center of the device. My agitator comprises opposed dished disks J and J' provided with a 90 threaded and non-threaded central aperture respectively. To these disks are secured diametrically opposed convex blades K. These blades are stamped out of metal and so fashioned to present a curved body portion K' from which extend spaced projections or teeth K². To stir up and propel the material to the center of the device one half of these teeth K², on each blade, are twisted at opposite angles so that half of the teeth 95 on each blade have a tendency, upon rotation of the agitator, to move the mass toward the opposite wall of the device. The blades may be secured in any convenient way to the disks J and J' but as shown have their ends 100 extending through slits cut therein at L. 105

To secure the proper positioning of the agitator in the device the upper section B is provided with diametrically opposed apertures M which are adapted to align with the 110 apertures in the disks J and J' respectively when the proper relation between the parts

2
is established. A rod N threaded at one end and provided with a bent over handle portion N' at its other end is adapted to be inserted through the aligned apertures to 5 form a fulcrum for the agitator, the threaded end engaging the threaded aperture in the disk J and extending through the adjacent aperture in the section B which forms a bearing therefor. In this position rotation 10 of the handle N' will also rotate the agitator.

With the construction thus far described assembly of the device is as follows: First 15 the agitator is formed into a unit and secured in the upper section B as brought out in the preceding paragraph. Then the sieve having the desired size mesh is placed in the lower section C so that its flanged edge will fit over the rolled upper edge of 20 the section C. The upper section is then hinged to the lower one by inserting the tongue B² through the loop C² of the wire C'. To lock the sections together the upper 25 section is first properly positioned so that its lower edge will rest flush with the curved edge of the sieve when the wire loop F³ is placed over the tongue G' and the handle F' pressed downward. This will draw the sections tightly together and lock them so 30 until the handle is moved upward to such a position as will bring the pivot of the wire loop F³ past the fulcrum of the handle F'. A cover O is then placed upon the 35 upper section. Whenever it is desired to use a different sieve it is only necessary to unlatch the sections and rock them apart upon the hinge D to a position which will permit of withdrawing the sieve therein and substituting the desired sieve in its place.

40 The invention as described comprises a relatively small number of parts which may be readily fashioned and assembled or completely taken apart.

What I claim as my invention is:—

45 1. A culinary utensil comprising a container formed of upper and lower sections respectively hingedly secured to each other, a sieve adapted to be secured between said sections, a latch member adapted to lock said sections together, comprising a struck-out projection on one of said sections and a member pivotally secured to the other of said sections and adapted to engage said projection, and an agitator rotatably mounted upon one of said sections.

50 2. A culinary utensil comprising a container formed of upper and lower sections respectively hingedly secured to each other, the upper edge of said lower section being rolled and the lower edge of said upper section being slightly curved, a sieve provided with a peripheral curved flange adapted to

fit over said rolled edge and form a seat for the curved edge of said upper section and means for locking said sections upon said 65 sieve to form a tight joint therebetween.

3. A culinary utensil comprising a container formed of upper and lower sections respectively, a handle secured to one of said sections and terminating at one end in a bent 70 over tongue portion, a wire secured adjacent the abutting edge of the other section and bent to form a loop for receiving said tongue, a latch member at the opposite side of said sections for securely holding and locking said 75 sections upon one another.

4. A culinary utensil comprising a container formed of upper and lower sections respectively, upturned tongue portions at the lower edge of said upper section and 80 wire loops secured adjacent the upper edge of said lower section and in alignment with said tongue portions, said wire loops being adapted to engage said tongue portions to form a hinge, and a latch respectively for 85 said sections.

5. A culinary utensil comprising a container formed of upper and lower sections hingedly secured to each other, a sieve secured between said sections, an agitator rotatably mounted in one of said sections and comprising a curved blade adapted to press the contents of said container against said sieve and spaced curved teeth on said blades half of each set of which are adapted to 95 propel the mass of contents toward the center of the container when the agitator is actuated.

6. A culinary utensil comprising a container formed of two sections having curved 100 abutting edges overlapping each other, and hingedly secured to each other, a latch carried by said sections and adapted to hold them tightly together, a sieve having a curved peripheral portion adapted to be secured between the curved abutting edges of 105 said sections and an agitator detachably secured to one of said sections.

7. A culinary utensil comprising a container formed of two sections hingedly secured together and adapted to be swung apart sufficiently to permit of insertion or withdrawal of a sieve element therebetween, means upon the adjacent edges of said sections for engaging the edge of said sieve, 110 a diametrically opposed latch and hinge respectively for securely clamping said edges together to form a tight joint therebetween, an agitator, and means engaging said agitator and extending through the casing of one 115 of said sections to form a mounting and actuating means therefor.

In testimony whereof I affix my signature.
IDA M. HEATH.
